UNITED STATES PATENT OFFICE

JOHN BLIZARD, OF GARDEN CITY, NEW YORK, ASSIGNOR TO FOSTER WHEEL CORPORATION, OF NEW YORK, N. Y., A CORPORATION OF NEW YORK

FUEL BURNER

Application filed December 17, 1927. Serial No. 240,695.

The present invention relates to the construction and operation of fuel burners and particularly to fuel burners through which a mixture of comminuted fuel and air is discharged into a combustion chamber. The object of my present invention is to provide an improved construction of a comminuted fuel burner which is characterized by improved means for regulating and directing the flow of the combustible mixture into the combustion chamber.

The various features of novelty which characterize my invention are pointed out with particularity in the claims annexed to and forming a part of this specification. For a better understanding of the invention, however, and the advantages possessed by it reference should be had to the accompanying drawings and descriptive matter in which I have illustrated and described a preferred embodiment of the invention.

Of the drawings:

Fig. 1 is an elevation in section of a preferred embodiment of my invention;

Fig. 2 is a section on the line 2—2 of Fig. 1;

Fig. 3 is a section on the line 3—3 of Fig. 1; and

Fig. 4 is a section on the line 4—4 of Fig. 1.

In the drawings I have illustrated a preferred embodiment of my invention mounted in a fuel inlet opening A' in a wall of a combustion chamber A. My burner comprises an outer casing structure B divided into three sections B', B² and B³. The section B' consists of a substantially conical shaped casing member forming a lining for the tapered outer portion of the Venturi-shaped fuel inlet opening A'. The middle section B² is substantially cylindrical in form and connected by annular flanges to the adjacent sections B' and B³. The section B² is positioned chiefly between the masonry wall structure and a metallic reinforcing beam A² of the furnace wall. The outer section B³ consists of a flared casing, having its enlarged inner end connected to the casing section B² and its outer end connected to a fuel conveying pipe B⁴, through which the combustible mixture of air and fuel is passed to the fuel inlet A¹.

Mounted within the casing B is a com-

posite mechanism for regulating and directing the flow of combustible mixture into the fuel inlet opening A'. This mechanism comprises a cylindrical inner casing member C, preferably concentric with the outer casing 55 section B² and closed at its outer end by an integral tapered end section C'. The cylindrical portion is provided with a plurality of integral radially projecting vanes C², extending longitudinally thereof. The vanes are angularly spaced 120° and act as spacers to definitely position the casing C with respect to the outer casing B. The outer edge of each vane C² is rounded off and arranged for slidable movement in a corresponding 65 groove B⁵ formed in the casing section B². Each vane is cut away along a line parallel to the inner side of the tapered casing section B¹ as shown at C⁴.

The tapered end of the casing C is formed with a threaded central opening C⁵. Projecting longitudinally from the outer end of the casing C towards the wall opening A' are a pair of semi-cylindrical guide members C⁶, having their adjacent sides spaced apart 75 along the vertical center line of the burner and arranged to form longitudinal guideways. The guides C⁶ are connected at a point adjacent their inner ends by a spider C⁷ detachably secured to bosses C⁸ on each member. The hub C⁹ of the spider is provided with an opening C¹⁰ therethrough.

The burner is arranged with a tip member D having a circular hollow outer end portion D' and a substantially conical inner end portion D². The outer section D' is cut away to form ribs D³ at the top and bottom thereof, which fit into the guideways formed by the semi-cylindrical members C⁶ as shown in Fig. 3. The tip D is made of heat resistant material, such as carborundum, to withstand the high temperatures adjacent that part of the inlet opening.

A diffuser member E is slidably mounted within the inner casing C between the guide members and casing and is formed of concentric cylindrical rings E' and E², integrally connected at spaced points about their circumference by radial flanges E³. A vertical reinforcing bar E⁴ extends across the outer 100

end of the ring E' and is arranged with an enlarged central hub portion E^5 having a threaded opening E^6 therein. As shown in Figs. 1 and 2 the reinforcing bar E^4 extends through the guidways formed by the guides E^8 , so that on a longitudinal movement of the diffuser member E , the bar E^4 moves along the guidways thereby preventing rotation of the diffuser. The rings E' and E^2 are integrally connected at their inner ends by an annular inclined wall E^7 , on which is formed a plurality of flow directing or diffuser blades K extending longitudinally of the burner. As shown in Fig. 3, each of the blades K is arranged at an angle to a tangent at the point of contact with the inner ring E' , which preferably is made about 45° . Each blade K has a flat side K' and a curved side K^2 tapering as it approaches the nozzle tip D . The inner end of each blade is cut away at an angle corresponding to the angle of the inner casing section B' with the burner longitudinal axis.

The outer casing section B^3 is provided with a boss M on the outer curved portion thereof. An opening is arranged in the boss M for the passage therethrough of a tube F , having a threaded inner end F' , secured in the threaded opening C^5 of the casing C . The tube F has a threaded outer end F^2 on which is secured a collar F^3 . Mounted on the collar F^3 is an indicator support F^4 to which is secured a stationary pointer F^5 , the upper end of which is bent over and pointed as at F^6 . An operating rod G is arranged within the tube F and provided with a threaded portion G' passing through the threaded opening E^6 of the bar E^4 . The inner end G^2 of the rod G is constructed of smaller diameter than the threaded portion G' and arranged to fit in the opening C^10 in the hub C^9 and is provided with a lock nut G^3 to hold the rod in position in the hub C^9 . Mounted on the reduced outer end G^4 of the rod is a hand wheel G^5 having its hub G^6 secured thereon. A collar G^7 is also mounted on the end portion G^4 and secured to the hub G^6 for rotation therewith. The upper side of the collar G^7 is provided with a projecting arm G^8 having its outer end bent to engage a curved notch L' in the bottom of an indicator disc L having indices marked on its periphery. The disc L is pivotally mounted on the arm G^8 and provided with similar notches L' extending around its circumference. The parts are so arranged that a complete rotation of the handwheel advances the disc one notch and the arm G^8 will then be in contact with the next notch.

The upper half M' of the boss M has a horizontal hinge connection with the lower half M^2 . The parts are provided with a suitable clamping lever M^3 which effects a clamping action of the boss parts on the tube F when the lever is in one position and permits longitudi-

nal movement of the tube through the boss when in another position.

With the apparatus constructed as described, a combustible mixture of comminuted fuel such as powdered coal, and air is passed upwardly through the conduit B^4 to the mixing chamber formed within the burner casing B as shown by the arrows in Fig. 1. The mixture passes around the outer side of the casing C and through the passages formed by the vanes C^2 , by which the flowing mixture is directed longitudinally, eddy currents substantially eliminated, and stratification of the fuel avoided.

The fuel and air mixture then passes through the annular channel formed between the burner tip D and the tapered casing section B' . On a rotation of the hand wheel G^5 the diffuser blades are correspondingly advanced into or withdrawn from that channel. The blades K effect a rotary movement of the portion of the combustible mixture adjacent thereto and contacting therewith and as the blades are further advanced into the channel a greater portion of the mixture will receive a rotary movement until at the extreme position of the diffuser blades K shown in dotted lines in Fig. 1, all of the mixture will receive a rotary movement. The rotative effect of the blades K provide a more uniform mixture of the fuel and air and the angular velocity of the mixture as it passes through the Venturi throat portion distributes the combustible mixture over a considerable portion of the combustion chamber.

The velocity of the stream of combustible mixture at the tip end D^2 may be varied by moving the tip D inwardly to decrease the effective discharge area of the throat passage into the combustion chamber. The tip is moved by releasing the clamp lever M^3 and sliding the whole internal burner structure longitudinally of the casing B . During this longitudinal movement, the vanes C^2 move in the grooves B^5 . The guide blades K are moved longitudinally with the burner structure and operate as described to give a rotary movement to the stream of combustible mixture. When the burner has been moved to the desired portion, the clamp lever M^3 is operated to lock the tube F in that position. The outer portion of the tube F is marked in suitably spaced lines F' to indicate the position of the burner tip within the opening to the combustion chamber.

A rotary movement of the hand wheel causes the projecting arm G^8 to turn therewith to rotate the disc L . The pointer being stationary indicates on the disc the relative longitudinal position of the blades K in the casing section B .

My invention thus comprises a comminuted fuel burner structure, the mechanism of which may be adjusted in a wall opening with respect to the combustion chamber to regulate

the mass flow of fuel and air or to regulate the velocity relatively to the mass flow. Parts of the burner mechanism can be independently moved to effect a rotary movement of the mixture as it is discharged. The indicating devices provided show the positions of the various parts relative to the opening to the combustion chamber. My invention is characterized by the simplicity of construction and effectiveness in operation of the composite structure. The uniform mixture of fuel and air obtained results in complete combustion of the fuel with a high operating efficiency. The indicating devices permit the use of relatively unskilled operating labor.

While in accordance with the provisions of the statutes, I have illustrated and described the best form of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features.

Having now described my invention, what I claim as new and desire to secure by Letters Patent, is:

1. The combination with a combustion chamber wall having a fuel inlet opening therein, of a comminuted fuel burner comprising a combustible mixture conveying casing communicating with said wall opening and flow controlling mechanism positioned within said casing and including means for varying the effective discharge area of said wall opening, and flow directing means for directing the flow of the combustible mixture to give a rotary movement thereto including provisions independently movable longitudinally in said casing to vary the rotary movement of said mixture during its passage through said wall opening, and mechanism operable independently of said discharge area varying means for moving said flow directing provisions.

2. The combination with a combustion chamber wall having a fuel inlet opening therein, of a comminuted fuel burner comprising a burner casing communicating with said wall opening and connected to a fuel conveying conduit at its outer end, flow controlling mechanism mounted within and spaced from said burner casing to provide a passage therebetween for the flow of a combustible mixture of fuel and air, a series of longitudinally extending transversely inclined flow directing blades mounted in said controlling mechanism, and means for projecting said blades from an initially ineffective position into said passage to effect a rotary movement of said combustible mixture.

3. The combination with a combustion chamber wall having a fuel inlet opening

therein, of a comminuted fuel burner comprising an outer casing communicating with said wall opening, and flow controlling mechanism mounted in said outer casing and including an inner casing radially spaced from said outer casing and forming an annular passage therebetween, a series of longitudinally extending transversely inclined flow directing blades mounted on said inner casing, and means for longitudinally moving said inner casing and blades relatively to said opening.

4. The combination with a combustion chamber wall having a fuel inlet opening therein, of a comminuted fuel burner comprising an outer casing communicating with said wall opening, flow controlling mechanism mounted in said outer casing and including an inner casing radially spaced from said outer casing and forming an annular flow passage therebetween, a series of longitudinally extending transversely inclined blades mounted within said inner casing, means for longitudinally moving said inner casing and blades relatively to said wall opening, and means for moving said blades longitudinally in said flow passage relatively to said inner casing.

5. The combination with a combustion chamber wall having a fuel inlet opening therein, of a comminuted fuel burner comprising an outer casing communicating with said wall opening, an inner casing radially spaced from said outer casing, a diffuser ring slidably mounted in said inner casing, flow directing blades mounted on said ring, a burner tip of refractory material mounted in said inner casing, means for simultaneously moving said ring and tip longitudinally of said outer casing, and means for independently moving one of said members longitudinally.

6. The combination with a combustion chamber wall having a fuel inlet opening therein, of a comminuted fuel burner comprising an outer casing communicating with said wall opening, an inner casing radially spaced from said outer casing and forming an annular flow passage therebetween, a pair of guide members mounted in said inner casing, a diffuser ring, flow directing blades connected to said ring, a refractory burner tip secured to said guide members, and means for simultaneously moving said casing, guide members and tip longitudinally in said wall opening.

7. The combination with a combustion chamber wall having a fuel inlet opening therein, of a comminuted fuel burner comprising an outer casing communicating with said wall opening, an inner casing radially spaced from said outer casing and forming an annular passage therebetween, a diffuser ring slidably mounted in said inner casing, flow directing blades mounted on said ring,

a refractory burner tip mounted in said inner casing, means for simultaneously effecting a longitudinal movement of said inner casing, diffuser ring, and tip, means for independently moving said diffuser ring, and means for indicating the position of said inner casing and tip relative to said wall opening.

8. The combination with a combustion chamber wall having a fuel inlet opening therein, of a comminuted fuel burner comprising an outer casing communicating with said wall opening, an inner casing radially spaced from said outer casing and forming an annular passage therebetween, a diffuser ring slidably mounted in said inner casing, a plurality of flow directing blades mounted on said ring, a refractory burner tip mounted in said inner casing, means for simultaneously effecting a longitudinal movement of said inner casing, diffuser ring, and tip, means for independently moving said diffuser ring, and means for indicating the position of said diffuser ring relative to said wall opening.

9. The combination with a combustion chamber wall having a fuel inlet opening therein, of a comminuted fuel burner comprising an outer combustible mixture conveying casing communicating with said wall opening, and flow controlling mechanism including an inner casing positioned within said outer casing and forming an annular flow passage therebetween, flow directing vanes on said inner casing and slidably mounted in said outer casing, a diffuser ring slidably mounted in said inner casing, guide means for preventing rotation of said ring in said inner casing, a plurality of transversely inclined flow directing blades projecting longitudinally from said ring, means for effecting a longitudinal bodily movement of said inner casing and ring, and means for independently moving said blades longitudinally of said wall opening.

10. The combination with a combustion chamber wall having a fuel inlet opening therein, of a comminuted fuel burner comprising an outer combustible mixture conveying casing communicating with said wall opening and flow controlling mechanism including an inner casing positioned within said outer casing and providing an annular flow passage therebetween, flow directing vanes secured on said inner casing and slidably mounted in said outer casing, a diffuser ring slidably mounted in said inner casing, guide means for preventing rotation of said ring in said inner casing, a plurality of transversely inclined flow directing blades projecting longitudinally from said ring, means for effecting a longitudinal bodily movement of said inner casing and ring comprising a tube extending externally of said outer casing and releasable clamping means mounted on said casing, and means for independently

moving said blades longitudinally of said wall opening comprising a longitudinally adjustable operating rod extending through said tube.

Signed at New York city, in the county of New York and State of New York this 14th day of December, A. D. 1927.

JOHN BLIZARD.
